GAS LIFT OIL RECOVERY SYSTEM

Robert L. Kirkpatrick, Verona, Pa., assignor to
 Gulf Research & Development Company, Pittsburgh, Pa., a corporation of Delaware

Application March 21, 1941, Serial No. 384,559

9 Claims. (Cl. 163—232)

This invention or discovery relates to gas lift oil recovery systems; and it comprises in an intermittent gas lift system for wells having the usual string of tubing extending down the well, a gas control valve in the lower portion of the tubing, a reciprocable member for alternately opening and closing the control valve and power means for reciprocating said member, the improvement comprising an electrical control circuit for the power means, including a float switch in fixed relation to the reciprocable member and arranged for operation by well liquid rising in the tubing to the level of the float switch so as to cause actuation of the power means upon rise of liquid to said level; all as more fully hereinafter set forth and as claimed.

A good modern type of intermittent gas lift oil recovery system makes use of a string of tubing extending from the top of the well down into the liquid in the well, and fitted with a lower standing valve and one or more gas inlet control valves in the tubing wall thereabove. The tubing is packed off below the control valve, and gas under pressure is maintained in the space outside the tubing. Oil flows into the lower part of the tubing under formation pressure. At regular (constant-rate) intervals the gas control valve is opened, by means of a sinker extending down to it on a cable, to start a slug of oil toward the surface. When the slug reaches the surface, the control valve is caused to close, and the cycle is repeated.

Such systems give good results if the control valve closing and opening intervals are correctly adjusted, but if the intervals are not correct the efficiency may be low. The correct operating rate is determined by trial and error; a tedious and difficult procedure in some cases. Moreover the adjustment is thrown out if the rate of influx of oil from the well varies, as often happens.

Proposals have been made for controlling gas lift systems with the aid of a float switch located in fixed relation to the tubing, but in such systems, if it is desired to change the effective level of the switch the entire string of tubing has to be withdrawn and reinstalled with the switch in a new position; a tedious and difficult operation.

Among the objects of the present invention are the provision of a gas lift system of the type described, in which means are provided for actuating the gas control valve in accordance with rise of liquid in the tubing to a predetermined level, thereby assuring maximum operating efficiency; and the provision of such a system in

which the predetermined operating level is readily changed with a minimum of complication.

These and other objects are achieved by the provision of an electrically controlled gas valve operating device in such systems, and a float switch, in fixed relation to the reciprocable sinker, and adapted to actuate the operating device on rise of liquid to the level of the float switch. This level is readily determined by changing the spacing of the float switch; an operation requiring merely withdrawing the float switch and sinker and putting in a new suspension of different length.

In the accompanying drawings I have shown diagrammatically two examples of specific embodiments of apparatus within the purview of the invention. In the drawings:

Fig. 1 is a view partly in elevation, partly in central vertical section, of the portion of one form of the apparatus which is installed in a well,

Fig. 2 is a similar view of a modified form.

Fig. 3 is a view in elevation of the part of the apparatus of Figs. 1 and 2 which is installed above ground, and

Fig. 4 is a detailed view partly in elevation and partly in central vertical section of one form of perforate cage containing the float and float actuated tip switch.

Fig. 1 shows the invention applied to a gas lift system including a string of eductor tubing 10 extending down a well cased at 11 and terminating at a casing head 9 (Fig. 3). The tubing and casing define an annular space 12 down which gas is pumped. String 10 is joined at 13 to an enlarged section 14 communicating with a gas control valve fitting 15 the valve 16 of which is opened and closed by a reciprocable sinker 17. The valve is shown in open position, depressed by the sinker. Fitting 15 communicates through a standing valve 18 with a bull plug fitting 19 extending into the well liquid (not shown) and packed off at 20. The sinker is reciprocated from the surface through the agency of a piston 22 and a lifting cylinder 21 suspended directly over the casing head (Fig. 3).

The use of the packer 20 is not always necessary but depends rather on the liquid level or bottom hole pressure in the well. If the liquid level in the well is high, a packer need not be used but if it is low a packer is necessary to prevent blow-by of the operating gas around the bottom of the tubing and to withhold operating gas pressure from the reservoir of oil

so that it will not seriously oppose the flow of oil into the well.

Sinker 17 is attached through a cable 25 to a perforate cage 26 containing a float 27 freely movable therein and adapted in its upper position to close a mercury tip switch 28, this construction being shown diagrammatically in Figs. 1 and 2 and in detail in Fig. 4. The cage and the sinker are reciprocated by a double electrical cable 29 attached to the cage and in electrical connection with the switch. The cable extends through a stuffing box 30 on the casing head to a clamp 31 attached to the piston rod 32 of piston 22.

Gas under regulated pressure is introduced into the casing head at inlet 35 and liquid and gas are discharged from the well at outlet 36.

The lifting cylinder 21 is operated on the up-stroke by gas pressure from 35, and on the downstroke by gravity. Admission of gas is controlled by a three way pneumatic valve 136 having two diaphragm power means 37 and 38 as shown, and adapted in one position to admit gas to cylinder 21 from fitting 35, through conduits 39 and 40, and in its other position (that shown) to exhaust the cylinder through conduit 43 and vent 41. The valve is shiftable to the right by pressure at diaphragm 38 through a branch conduit 42, as shown, and shiftable to the left by pressure from outlet fitting 36, applied to diaphragm 37 through a conduit 43. Branch 42 has a restricted-orifice fitting 50, a pressure regulator 150 and a bleed-off vent 44 normally open but closable by a weighted lever valve 45 on energization of a solenoid 46 operating on one end of the lever valve as shown.

The wires of cable 29 are in circuit with a source of electrical energy shown as a battery 47, a switch 48 openable at the top of the piston upstroke and the solenoid 46.

The apparatus operates in a cyclic manner as follows:

Liquid flows into the tubing through fitting 19 and rises to cage 26, causing the float to close the tip switch. Switch 48 being closed at this time, solenoid 46 is energized by battery 47 closing bleed-off 44. Pressure builds up at diaphragm 38, moving the valve 136 to position such that gas under pressure flows through 39 and 40 and raises piston 22. This lifts sinker 17 into the position shown in Fig. 1, opening valve 16 for admission of gas into the body of liquid in the tubing. At the top of the stroke of piston 22, switch 48 is opened, thereby opening bleed-off 44. Pressure is released from diaphragm 38. To ensure proper release, the effective orifice of the bleed-off is made larger than that of orifice fitting 50.

With the opening of valve 16 a slug of liquid (not shown) is started to the surface. When it reaches the well head and flows out through outlet 36 its pressure is transmitted to diaphragm 37, through duct 43, thus causing the three-way valve to shift to the position shown in Fig. 3, venting lift cylinder 21. The piston moves downward, valve 16 closes and the cycle is completed. When liquid again builds up to the level of the float switch, the cycle is repeated.

The distance between the sinker 17 and the cage 26 determines the amount of liquid for each slug. If it is desired to change the amount of liquid per slug it is merely necessary to withdraw cable 29 which carries the cage and the

sinker, and fit a new suspension 25 of different length. In some installations a plurality of gas control valves are provided at spaced intervals up the tubing, all operated by a reciprocable sinker in a manner similar to that described. The present improvement is applicable to such systems, and in such cases the location of the sinker may be changed simply by changing the distance between the float switch and the sinker where there is sufficient gas pressure for lifting larger slugs of oil, or by progressively lowering the switch and sinker to the particular control valve at which it is desired to operate.

In Fig. 2 I have shown a modified form of apparatus which has advantages in some utilizations. Gas is introduced at the top of an accumulation chamber, to force liquid down the outside and then up inside the eductor tube; an arrangement which results in more solid slugs of liquid, so to speak, than when gas is merely introduced into the bottom of a charge of liquid in the usual way. As shown, tubing 10 is connected through a concentric enlarged section 55, defining an annular passage 56, to a bull plug 61 and standing valve 18. A control valve 58 is provided in section 55, adapted to be opened on the upstroke of a hollow, tubular sinker 57 to admit gas into passage 56. Actuation of valve 58 by the sinker is through a reciprocable operating pin 158 positioned opposite the valve in the wall of the tubing 10. Section 55 is packed off at 62 below the valve. The float switch assembly 26, 27, 28 is suspended below the sinker, as shown. If desired the float switch assembly and the sinker may be incorporated in a single unit.

In operation, liquid builds up in the annular space 56 and tube 10 to the level of the float switch, whereupon sinker 57 is raised to open valve 58 through reciprocation of pin 158 and gas is introduced on top of the liquid charge in the annular space. A slug of liquid is thereby started on its way to the surface. The operating cycle of the apparatus of Fig. 2 is like that of Fig. 1.

Fig. 4 shows one form of construction of perforate cage, float, and float actuated tip switch assembly useful in the practice of the present invention. In this showing, cage 26 consists of a section of metal tube closed at its lower end and provided with perforations 75 in its side walls. The upper end of the tube is threaded to receive cable socket 76 in which cable 77 is secured in conventional manner as by swedging, leading or the like. Clamped between the top of the cage and an internal shoulder 78 on the cable socket is a threaded plug 79 through which the electric wires 80 of the cable pass into the cage and connect with the switch as shown. The mercury tip switch 28, of conventional insulated construction, is supported by a pair of yoke members 81 and 82 respectively, formed of fiber or other non-conducting material. Yoke 81, as shown, is shorter than yoke 82 and is pivoted at 83 to a bracket secured to the wall of the cage. The longer yoke member 82 projects from below the switch to a position where it may be struck by the float 27. The float consists simply of a hollow sealed cylindrical metal can. Since the upward travel of the float need be sufficient only to close the switch by tilting it about pivot 83, stops 84 secured to the side walls of the cage are provided for engaging the top end of the float opposite its reduced end 85 for limiting upward travel.

In all embodiments the slug of liquid is started to the surface only when the liquid has built up to a predetermined level. This insures delivery of the maximum desired (or maximum permissible) slug at each cycle. If the rate of influx of oil from the well to the tubing varies, the time period for each cycle varies correspondingly, always insuring complete efficiency.

What I claim is:

1. In a gas lift pump of the type wherein a wire line suspended sinker is alternately raised and lowered in a well for controlling the operation of bottom hole gas valve including means for raising and lowering the wire line and sinker, the improvement which comprises, an electric circuit including a source of electricity, electrically operated means for controlling the movement of the wire line in one direction and a pair of switches in series electrical connection with the source of electricity and said electrically operated means, one of said switches being adjustably suspended in the well and operated by the rise and fall of the level of liquid in the well, the other of said switches being operated by the means for raising and lowering the wire line, and means operated by the delivery of a slug of oil to the top of the well for controlling movement of the wire line in the opposite direction.

2. In a gas lift pump of the type wherein a reciprocable member is alternately raised and lowered in a well for controlling the operation of a bottom hole gas valve, the improvement which comprises an accumulation chamber, an eductor tube in said chamber through which the member is adapted to be raised and lowered, a control valve in the wall of said chamber and control valve operating means in the wall of the eductor tube opposite the control valve, said control valve operating means being arranged for actuation by the reciprocable member.

3. The subject matter of claim 2 in which the reciprocable member is a hollow tube.

4. In a gas lift pump of the type wherein a wire line suspended sinker is alternately raised and lowered in a well for controlling the operation of a bottom hole gas valve, the improvement which comprises an accumulation chamber in the well, an eductor tube in said chamber through which the sinker is adapted to be raised and lowered, a control valve in the wall of said chamber, control valve operating means in the wall of said eductor tube opposite the control valve, said control valve operating means being arranged for actuation by the sinker, power means adapted for operation to raise the sinker, an electrical circuit for controlling the operation of the power means and a float switch in said electric circuit, carried by the wire line, said switch being located in the tubing and vertically spaced from said sinker at a predetermined level relative thereto and arranged for operation upon rise of well liquid in the tubing to said level to cause operation of the power means.

5. In an intermittent gas lift system for wells including a string of tubing extending down the well, a normally closed gas control valve in the

tubing, a member reciprocable in the tubing to open the valve and power means for raising said member, the improvement which comprises an electrical control circuit for controlling the operation of the power means, said circuit including a float operated electric switch associated with said member for reciprocation in the tubing therewith, said switch being adapted for operation by the liquid in the tubing.

6. The subject matter of claim 5 wherein the reciprocable member is a hollow tube.

7. In an intermittent gas lift system for recovering liquids from wells, including a string of tubing extending from the surface down the well to a point beneath the level of the liquid therein, a gas control valve in the tubing and power driven means adapted for operation to move said valve from one operating position to another, the improvement which comprises an electrical control circuit for controlling the operation of the power means, said circuit including an electric switch in the tubing, said switch being actuated by the liquid in the tubing at a predetermined level of the liquid and being removably positioned at said level, and means for positioning and removing the switch from said level by simply lowering and raising the same through the tubing.

8. In an intermittent gas lift system for wells including a string of tubing extending down the well, a normally closed gas control valve in the tubing, a reciprocal member in the tubing adjacent the valve and power means at the surface adapted for operation to move said member to open the valve, the improvement comprising an electric circuit for controlling the operation of the power means, said circuit including a float actuated switch in the tubing adapted to be actuated by the rise of the level of the liquid in the tubing, and means extending to the top of the well for adjustably locating the switch relative to the tubing and the liquid in the tubing, at any desired level for actuation of the switch by the rise of liquid to said level.

9. In an intermittent gas lift system for wells including a string of tubing extending down the well, a normally closed gas control valve in said tubing, a sinker reciprocable in the tubing to operate the valve, power means at the surface of the well, and a cable connecting the sinker with the power means for raising and lowering the sinker, the improvement comprising an electrical control circuit for controlling the operation of the power means, a float operated electric switch in said circuit, said switch being adapted to be suspended in the tubing by said cable in fixed spaced relation to the sinker and adapted for operation by the rise of liquid in the tubing to a predetermined level, and means whereby said sinker and switch may be removed from the tubing to the surface for changing said fixed spaced relation and thereafter replaced in the tubing by simply raising and lowering the same through the tubing.

ROBERT L. KIRKPATRICK.
